UNITED STATES PATENT OFFICE.

ANDREW W. KOSKI AND THOMAS CASEY, OF FITCHBURG, MASSACHUSETTS.

PIN-FASTENER.

1,375,033.

Specification of Letters Patent. Patented Apr. 19, 1921.

Application filed October 30, 1920. Serial No. 420,756.

To all whom it may concern:

Be it known that we, ANDREW W. KOSKI and THOMAS CASEY, citizens of the United States, residing at Fitchburg, in the county 5 of Worcester and State of Massachusetts, have invented certain new and useful Improvements in Pin-Fasteners, of which the following is a specification, reference being had to the accompanying drawings.

10 This invention relates to improvements in pin fasteners.

An important object of the invention is to provide means for fastening the piercing ends of brooch bar pins or the like which is 15 free from the use of springs in its construction, thereby providing a device which is comparatively long lived.

A further object of the invention is to provide a device of this character having 20 as few working parts as possible and having its working parts of such formation that they may be readily formed by die-stamping the same from sheets of metal, thereby materially reducing the cost of construction.

25 A still further object of the invention is to provide a device of this character in which the locking of the pin is accomplished by the closing of the pin and is positive in its nature.

30 Other objects and advantages of the invention will become apparent throughout the course of the following description.

In the accompanying drawings, wherein 35 for the purpose of illustration is shown a preferred embodiment of our invention, and wherein like reference characters designate like parts throughout:

Figure 1 is a side elevation partly in section of a pin fastener constructed in accordance with our invention;

Fig. 2 shows the fastener engaged by the pin;

Fig. 3 shows the pin completely locked 45 by the fastener, and

Fig. 4 is a section on the line 4-4 of Fig. 1.

Referring now more particularly to the drawings, the numeral 10 indicates a bar 50 having secured to one end thereof outstanding ears 11 forming supports for a pivot 12 upon which is mounted a pin 13.

The opposite end of the bar is likewise provided with upstanding spaced ears 14 55 adapted to receive therebetween the point of the pin 13, the edges of the ears 14 next

adjacent the ears 11 being provided with divergent guiding portions 15 for directing the point of the pin between the ears.

Mounted in the ears 14 is a pivot pin 16 60 upon which is mounted for oscillation a plate 17. This plate has formed therein a slot 18 which forms in the plate an overhanging portion 19 and a striking portion 20. When the plate 17 is so positioned that the overhanging portion 19 is approximately vertically directed, if the pin 13 is moved downwardly, it will engage the striking portion 20 and enter into the slot 18 causing the plate to rotate until the overhanging portion 19 overlies the point of the pin. 65 It will be seen that if means is provided for locking the plate in the last named position, the pin may be removed until such locking means disengage.

70 Such locking is shown in the accompanying drawings. The plate 17 is provided with what may be termed a dog-receiving notch 21 opposed to the notch 18. Pivotedly mounted intermediate the ears 14 is a second plate 22 embodying spaced arms 23 and 24, hereinafter to be referred to as the dog and operating arm, respectively. This plate is likewise provided with a thumb piece 25 which normally extends downwardly and engages against the end of the bar.

75 While the plate is in the position illustrated in Fig. 1 if the pin is moved downwardly the point thereon engaging against the striking piece 20 will cause the plate 17 to rotate. During this rotation, after the overhanging portion 19 is so positioned that it overlies the end of the pin, the under surface of the striking piece 20, as indicated at 80 26, engages against the extremity of the operating arm 24 causing the plate 22 to shift about its pivot. At this time the notch 21 is aligned with the dog 23 so that the dog 23 may enter the same and further downward 85 movement of the pin causes the dog to seat firmly in the closed position. The plates 17 and 22 will, of course, have a certain degree of frictional engagement with the adjacent faces of the ears 14 in order to prevent accidental displacement thereof. When the plate 17 is in the locking position and the plate 22 shifted so that the dog thereof engages in the notch 21, the thumb piece 25 is 90 shifted away from the end of the bar 10. 105 When it is desired to release the pin from its locking engagement this may be readily

accomplished by moving the thumb piece 25 inwardly to engage the end of the bar, in which position the plate 17 may be rotated to release the pin. In addition to the 5 binding engagement of the plates 17 and 22 with the surface of the ear 14, it is found desirable that the dog 23 during its movement both into and out of the notch 21 should have a slight binding engagement 10 with the outer surface of the plate in order that the movement of the plate 17 both into and out of the locking positions may be accomplished with a slight snap. For this reason the dog 23 is provided upon its inner surface with a small lug, as at 27.

It will be obvious that the construction hereinbefore set forth, by reason of its simplicity, durability and the ease with which it may be manufactured, is particularly 20 well adapted for the purpose for which it is intended; and it will likewise be obvious that the construction hereinbefore set forth may be somewhat altered without in any manner departing from the spirit or use of 25 our invention. We, accordingly, do not limit ourselves to the specific structure hereinbefore set forth, except as so limited by the subjoined claims.

What we claim is:

30 1. In a pin fastener, the combination with a pin pivoted to swing in a given direction, a pivot plate mounted in the path of the free end of the pin and pivoted to swing in the same plane therewith, said plate being provided with an overhanging portion, said pin upon its engagement with said plate rotating the same and causing said overhanging portion to overlie the free end of the pin, a second plate provided with a dog, a dog-receiving notch formed in the first named plate, means actuated by the rotation of the first named plate for rotating the second named plate to bring the dog thereof into engagement with said notch, the engagement 45 of the dog within said notch preventing the rotation of the first named plate in a direction opposite to the direction of rotation imparted thereto by said pin.

50 2. In a pin fastener, the combination with a body portion having a pin pivotally connected therewith to swing in a given plane, of a pair of spaced ears approximately parallel to and arranged upon opposite sides of the plane of swing of said pin, a plate pivotally connected intermediate said ears and provided with a slot forming in said plate an overhanging portion and a striking piece causing rotation of said plate

and causing said overhanging portion to overlie the free end of the pin and means 60 actuated by the rotation of said plate for positively locking the plate against rotation.

3. In a pin fastener, the combination with a body portion having a pin pivotally connected therewith to swing in a given plane, of a pair of spaced ears approximately parallel to and arranged upon opposite sides of the plane of swing of said pin, a plate pivotally mounted intermediate said ears 70 and provided with a slot forming in said plate an overhanging portion and a striking piece causing rotation of said plate and causing said overhanging portion to overlie the free end of the pin and means actuated by the rotation of said plate for positively locking the plate against rotation, comprising a second plate pivotally mounted intermediate and embodying a dog and an operating arm, said first named plate having a notch formed 75 therein and opposed to said slot, a portion of said first named plate engaging said operating arm and causing rotation of said second named plate to bring the dog thereof into engagement with said notch. 85

4. In a pin fastener, the combination with a body portion having a pin pivotally connected therewith to swing in a given plane, of a pair of spaced ears approximately parallel to and arranged upon opposite sides 90 of the plane of swing of said pin, a plate pivotally mounted intermediate said ears and provided with a slot forming in said plate an overhanging portion and a striking piece causing rotation of said plate and causing said overhanging portion to overlie the free end of the pin and means actuated by the rotation of said plate for positively locking the plate against rotation comprising a second plate pivotally mounted intermediate 95 and embodying a dog and an operating arm, said first named plate having a notch formed therein and opposed to said slot, a portion of said first named plate engaging said operating arm and causing rotation of said second named plate to bring the dog thereof into engagement with said notch, said dog 100 having a binding engagement with the edges of the first named plate during its movement into and out of engagement with said notch. 105

In testimony whereof we hereunto affix our signatures.

ANDREW W. KOSKI.
THOMAS CASEY.
